DISPLAY DEVICE

William W. Naramore, Bridgeport, Conn.

Application March 2, 1932, Serial No. 596,269

6 Claims. (Cl. 211—1.5)

This invention relates to improvements in advertising display machines or devices.

It is the object of the present invention to provide a novel and attractive means for displaying

various articles of merchandise in windows and elsewhere, which will have greater animation than ordinary display machines and thereby attract the attention and pause of a greater number of people who might otherwise just pass by.

10 To this end, the present invention provides one or more series of display supports with a mechanism for moving them in a sinuously circular path. When two series of display supports are provided they are driven in opposite directions

15 in two separate sinuously circular paths which intersect each other, yet in such manner that the supports are made to pass by each other without jamming even though the two series moves over the path of each other. All of this is accomplished with a comparatively simple mechanism.

One of the important features of the present invention is the provision of a central display unit which may be rotated coordinately with the operation of the hereinbefore described main display supports which travel in a sinuously circular path. In some aspects of the present invention this central display unit and support therefor are interchangeable so that various forms of the central units may be placed on the machine according to the articles which are to be displayed thereon and the type of display which the store owner wishes to effect.

According to the present embodiment of the invention, special lighting effects are also provided so that the articles on either or both the central display unit and the sinuously traveling display supports may be lighted. Also, if desired, and as shown, auxiliary display supports may be provided which may be rotated conjointly with the sinuously traveling supports and the central work table.

Other objects and advantages will hereinafter appear.

In the drawings—

45 Figure 1 is a side elevation of the display device of the present invention with sections broken away to more clearly show the operating mechanism.

50 Fig. 2 is a fragmentary detail view, partly in section, of the central table and the driving shaft therefor.

Fig. 3 is a side view of an auxiliary type of central display table.

55 Fig. 4 is a top plan view of the display member shown in Fig. 3.

Fig. 5 is a top plan view of the display device of the present invention, taken on line 5—5 in Fig. 1.

Fig. 6 is a top plan view similar to Fig. 5, but with the article supports removed and with the guideway plate partially removed, taken on line 6—6 in Fig. 1.

Fig. 7 is a fragmentary view of the display support driving means of the present invention.

Fig. 8 is a schematic view showing that portion of the guideway plate which overlies that section of the driving means shown in Fig. 7.

In its present preferred form the advertising display device of the present invention comprises a frame 10 including a base 11 having legs or standards 12 fastened thereto with screws 13 and adapted to support a bottom plate 14 at their top ends, which is fixed thereto with bolts 15 and nuts 16. This bottom plate supports an upper guide plate 17 which is mounted on a plurality of spacing collars 18 that rest on the bottom plate while bolts 19 and nuts 20 serve to hold the parts together.

The guide plate 17 serves a very important function and its construction should therefore be particularly noted. In its present preferred form it comprises an outer rim plate 21, which is mounted on the collars 18 in the manner just described. It also comprises an inner rim plate 22 mounted on sleeves 23 of the same height as spacing collars 18 which, through the medium of screws 24 threaded into the bottom plate 14, is clamped to the latter. The outer rim plate 21 is provided with a plurality of concave tracks 25 merging together at inwardly projecting points 26 and the inner rim plate is similarly provided with concave tracks 27 which merge at outwardly projecting star points 28 to partially form two guideways 29 and 30, respectively.

Between these tracks there is provided a plurality of quoits 31, slightly irregular in shape with convex tracks 32 and 33 which, in general, follow the outline of the concave tracks 25 and 27, but spaced slightly therefrom, so as to form the guideways 29 and 30. The quoits 31 are rigidly held in place by bolts 34 passing therethrough and through spacing sleeves 35 which rest upon the bottom plate 14, when the bolts are tightened in the bottom plate.

Thus, it will be seen that when the outer and inner rim plates 21 and 22 and the quoits 31 are fastened to the bottom plate 14 there is provided two guideways 29 and 30 which pass in a sinuously circular path about the axis of the machine, each guideway passing inwardly and then out-

wardly over the other guideway a number of times.

These guideways 29 and 30 are, according to the present invention, used to guide two sets 36 and 37 of the main display supports 38 in a sinuously circular path about the axis of the machine in such manner that the supports weave in and out between each other in a manner intended to attract the attention of passers-by.

10 The supports each comprise an elongated guide shoe 39 of the same width as the guideways, with an upper flange 40 adapted to overly the concave and convex tracks defining the guideways and limit downward movement of the carrier and to prevent tilting. If desired, each support may also be provided with a lower flange 41 adapted to extend over the underside of the concave and convex tracks. At its upper end the main supports are provided with article tables 42 which may be made integral therewith or may, 15 as shown, be made as a separate disk having a removable connection 43 thereto.

One set of display supports 38, those traveling in the clockwise direction, see Fig. 5, are assembled to the guideway 30 by sliding them through a dovetail slot 44 in the outer rim plate 21 and after the desired quantity are added a plate 45 is forced into the dovetail slot. The second set 37 of display supports 38 which travel 20 in a counterclockwise direction as shown in Fig. 5 are assembled to the guideway 29 through a dovetail slot 46 cut in the inner rim 22, after which a plate 47 is forced in the dovetail, as shown in Fig. 6, to close the guideway and prevent accidental removal of the display supports.

Projecting below the shoes 39 of the supports 38 are lugs or horns 48 adapted to slide into radial slots 49 and be engaged by radial arms 50 on the flanges 51 and 52 of horn gears 53 which are arranged beneath the quoits 31. Referring to Figs. 1 and 6, the horn gears 53 are journaled on the spacing sleeves 35 and the latter serve as bearings therefor after they are held in place with the bolts 34, as hereinbefore described, while the gears form a circular train arranged with their teeth intermeshing in such manner that alternate gears are driven in opposite directions as indicated by the arrows in Figs. 6 and 7. Each of the gears is provided with four radially projecting arms 50 and slots 49. The arms on alternate gears are on different planes which, as may best be seen in Figs. 1, 6 and 7, comprising the low arms on the gears with low flanges 51 and high arms on the gears with high flanges 52 so that they will not interfere with each other during rotation.

The radial arms 50 engage with the horns 48 and serve to propel the set 36 of main display supports 38 in a clockwise direction and propel the other set 37 of supports in a counterclockwise direction. A driver gear 55 which may have any suitable connection with a prime mover 56 rotates the meshing horn gear 53 in a clockwise direction and the latter gear in turn rotates all of the gears in the train in clockwise and counterclockwise direction as shown by the arrows in Figs. 6 and 7.

Operation of this part of the advertising display machine is as follows. As the horn gears 53 are rotated in clockwise and counterclockwise direction the radial slots 49 therein move into a position directly above each other at the point of intersection of the guideways 29 and 30, as is best shown at 57 in Fig. 7. At this point of 75 intersection the horn gears and in particular the

radial arms 50 carried thereby have the characteristic of engaging the horns 48 and moving the main display supports 38 in both clockwise and counterclockwise directions dependent upon which of the two guideways 29 or 30 the display support is in, e. g. if the horn 48a shown in Fig. 7 is a part of one of the display supports 38 in the guide 30 the guide shoe 39 portion thereof would be positioned like the shoe 39a shown by dot-and-dash lines in Fig. 8 and since it cannot turn into the guideway 29 at this point the lower radial arms part of the low flange 51 on the horn gear in Fig. 7 moving in a counterclockwise direction will engage the horn to carry it in a generally clockwise direction through the slot 30. 15 However, if the horn 38a is for a display support in the guideway 29 and projects in the direction indicated by the shoe 39b in Fig. 8 it cannot move into the guideway 30 and consequently the upper radial arms portion of the clockwise moving gear 53 with a high flange 52 engages the horn and serves to move it in a generally counterclockwise direction in the other guideway 29.

Because the gears 53 all contain the same number of teeth it is possible to maintain a constant 25 relationship between the radial arms 50 and there is no danger of one set of radial arms moving one display support 38 into the path of another. As the horn gears alternately move one display support 38 inwardly toward the axis of 30 the machine in a clockwise direction in the guideway 30 and then the next succeeding support outwardly relative to the axis in a counterclockwise direction in the guideway 29 and as the same display supports are moved in reverse direction relative to the axis when they reach the next point of intersection there is produced a fascinating effect which attracts and holds the interest of any person viewing the machine.

The driving mechanism 58 in the present preferred form of the invention, comprises a speed 40 reducing mechanism 59 having a suitable connection 60 with an electric motor 56 or other prime mover. The speed reducing mechanism preferably comprises a one piece bracket 61 attached to the bottom plate 14 with screws 62 which supports the horizontal shaft 63 and vertical shaft 64 journaled in standards 65 and 66 respectively. It is merely necessary to slide a worm 67 between the standards 65 past the shaft 63 therethrough 50 and then lock the shaft against longitudinal displacement by tightening a set screw 68 in the worm gear. A cooperating gear 69 is passed between bracket standards 66 and into engagement with the worm 67 whereupon the shaft 64 is moved 55 vertically into place as shown in Fig. 1 and the gear fastened thereto with a set screw 70. At the same time a driving pulley 71 and the driver gear 55 are similarly assembled and connected to the shaft 64 with screws 72 and 73 respectively. 60

As the connection 60 is driven by the prime mover 56 the shaft 63 rotates the worm 67 which in turn through its connection 60 with the gear 69 rotates the shaft 64, pulley 71 and driver gear 55, and the latter through its connection with one of the horn gears 53 rotates the entire train of horn gears to drive the display supports 38 through the guideways 29 and 30 in opposite directions and in spaced relation in the manner hereinbefore described.

If preferred, only a guideway 29 or 30 and a single series 36 or 37 of display supports 38 may be used in which event there will be a uni-directional travel of the set of display supports in a sinuously circular path. However, a more fasci- 75

- nating effect, and one which is certain to attract greater attention is accomplished by providing the two sets 38 and 37 and driving them in opposite directions and across the path of each other.
- 5 The present invention also provides a novel central display member 74 which may be rotated conjointly with the main display supports 38, preferably continuously in one direction, and as shown the machine is arranged to support different 10 styles of central display members. As shown in Fig. 1 the central display members 74 is provided with two tables 75 and 76 for supporting various articles of merchandise and as shown in Figs. 4 and 5 an auxiliary central display member 74a is provided with a small top table 77 and six angularly disposed side tables 78 upon which various articles of merchandise may be attached. Other 15 forms of central display members may be provided.
- 20 The mechanism for supporting and rotating the central display members 74 and 74a comprises a bracket 79 fixed to the underside of the bottom plate 14 with bolts 80. A central spindle 82 is suitably journaled in bracket standards 81 and in the lower plate 14 so as to carry a lower pulley 83 and an upper pulley 84 which are fixed thereon against rotation with set screws 85 and 86 respectively. The upper end of the spindle is adapted to slide into a suitable socket 87 in the lower end of the central display members 74 and 74a and is provided with a stop collar 88 which limits downward vertical movement of the member thereon. This stop collar is provided with a pin 89 adapted to engage with a notch 90 in the lower end of the central member which serves as a driving dog to insure rotation of the central display member conjointly with the spindle. Preferably, the spindle 82 is arranged to extend upwardly into the socket 87 a considerable extent 25 to thereby lessen the possibility of the central display member tilting. A belt 91 is assembled upon the pulleys 83 and 84 to effect rotation of the central spindle 82 conjointly with the rotation of the vertical shaft of the driver mechanism.
- 40 Thus, it is possible to place articles of merchandise which would be too large for the weaving display supports 38 on the tables 75 and 76 of the central display member 74 or on tables 77 and 78 of the central member 74a and thereby 45 display them with a certain amount of animation. Also, it is possible for a window dresser or store worker to prepare one auxiliary central carrier, for instance, the carrier 74a shown in Figs. 4 and 5, during spare moments without tying-up the 50 advertising display device, and easily and quickly change from one form of central carrier to another by sliding one off and the other one on the central spindle. Similarly, an auxiliary set of article 55 tables 42 portion of the display supports 38 may be provided so that they may be loaded during spare moments without tying-up the machine, and when they have been prepared merely remove the working set from the machine and add the newly prepared set as permitted by the 60 removable connection 43.
- The entire frame 10 and driving mechanism 65 may be easily and quickly enclosed by a cover 92 which is made in the form of a box with an open bottom and provided with cleats 93 on the side walls adapted to engage with the base 11 to limit vertical movement of the box. It is otherwise located by the base 11 fitting within the four side walls of the box. It may be provided with a 70 large circular cut-out as indicated by the dotted line 94 in Fig. 5 so that it may be put in place

after the article tables 42 of the display supports 38 are assembled or it may be provided with a cut-out 95 conforming with the concave tracks 25 and points 26 of the top plate to provide a more complete closure of the top of the device.

Special lighting effects are also provided by the present invention which add to the attractiveness and attention centering qualities of the device. In its present preferred form this is accomplished by clamping a pair of yielding contacts 96 and 97 on a fibre sleeve 98 with screws 99, all of which in turn are fastened to the lower plate 14 with a screw 100 and nut 101, and by providing a pair of rotatable contacts 102 and 103 on a fibre sleeve 104 portion of the central 10 display member 74 which engage with the yielding contacts. A pair of feed wires 105 and 106 having a connection with any suitable source of current are connected to the yielding contacts 96 and 97 respectively and other wires 107 and 108 20 are connected to the rotatable contacts 102 and 103 respectively and pass upwardly in the central member 74 through a wire clearance hole 109 for suitable connection to lower lamps 110 mounted on the underside of the table 76 and 25 connection to an upper lamp 111 within a shade 112 shown in Fig. 1.

When the central member 74 is assembled to the spindle 82 the rotatable rings 102 and 103 align with and engage the stationary contacts 30 96 and 97 so that current flows through the feed wires 105 and 106, stationary contacts 96 and 97, thence through rotatable contacts 102 and 103, and wires 107 and 108 respectively to provide current for the lamps 110 and 111 even 35 though the central display member 74 rotates. If preferred, the rotatable contacts may be notched slightly or provided with raised fibre plugs 113 so that engagement with the stationary contacts 96 and 97 will be intermittent and thereby cause the lamps to be intermittently furnished with current, causing them to flash on and off. Any suitable switch may be provided in the feed line 105 and 106 so that no current will be passed to the lamps in the event that it is 40 preferred not to use the lighting arrangement just described, or to disconnect lamps during the daytime when no artificial lights are required.

If desired, auxiliary display supports 114 may 50 be provided to add further to the effectiveness of the advertising display device of the present invention. In the present preferred form these auxiliary display supports have a removable connection 115 with vertical shafts 116 which 55 are suitably journaled in an upper standard 117 portion of the frame 10 and a lower standard 118 mounted on the base 11. Between these standards there is provided pulleys 119 and 120 having a set screw connection with the shaft 116 60 to limit vertical movement of the latter. A pair of belts 121 extend from the central shaft pulley 83 to the auxiliary shaft pulleys 119 and 120 and serve to rotate the latter conjointly with the rotation of the central shaft 82. This arrangement is such that the auxiliary supports 114 rotate continuously in one direction while the main display supports 38 are moved in a sinuously circular path, and are driven by the same prime mover.

It will be understood that portions of the device may be used without others, e. g., either one or two sets of main display supports 38, the auxiliary display supports 114, or the central display member 74 may be used; however, it is 70 75

preferable to use both the main display supports 38 which travel in a sinuously circular path together with the central display member, and in some instances also use the auxiliary display supports 114.

Other variations and modifications may be made within the scope of this invention and portions of the improvements may be used without others.

Having thus described the invention, what is claimed as new, and for which it is desired to obtain Letters Patent, is:—

1. In a merchandise display device, a box having a platform provided with a sinuously circular guideway; a series of table-like merchandise display supports adapted to move in said sinuous guideway; and a plurality of rotatable drivers supported with the box under said sinuous guideway and provided with radiating arms which are adapted to engage with the display supports and push them along in the sinuous guideway.

2. In a merchandise display device, a box having a platform having two sinuously circular guideways; two series of table-like merchandise display supports, each series being located in and guided by one of the sinuous guideways; and a plurality of rotatable drivers supported with the box under the sinuous guideways and provided with radiating arms adapted to engage display supports of the two series and move each of the latter through its respective guideway, one series in the opposite direction to that of the other.

3. In a merchandise display device, a box having a platform having two concentric superposed sinuously circular guideways arcuately offset so that their paths intersect each other; two series of table-like merchandise display supports located in said guideways; and a plurality of rotatable drivers spaced on a circular line defined by the intersecting points of the sinuous guideways, said drivers each being adapted to engage the display supports at the point where the sinuous paths intersect and move the display supports of one series in a clockwise direction and those of the other series in a counterclockwise direction through their respective guideways from the points of intersection to adjacent points of intersection.

4. In a merchandise display device, a box having a platform having two concentric superposed sinuously circular guideways arcuately offset so that their paths intersect each other; two series

of table-like merchandise display supports located in said guideways; a plurality of rotatable drivers spaced on a circular line defined by the intersecting points of the sinuous guideways, said drivers each being adapted to engage the display supports at the point where the sinuous paths intersect and move the display supports of one series in a clockwise direction and those of the other series in a counterclockwise direction through their respective guideways from the points of intersection to adjacent points of intersection; and means for moving alternate drivers in opposite directions of rotation whereby the paths of the two series of display supports repeatedly cross as the supports are advanced, said table-like display supports being of such size with relation to the guideways that the tables appear to barely pass each other in their movement around the guideways.

5. In a merchandise display device, a box having a platform provided with two sinuously circular guideways; two series of table-like merchandise display supports, each series adapted to move in one of said sinuous guideways; a plurality of intermeshing rotatable gears; a prime mover having a connection with one of said gears, and through the intermeshing arrangement driving all of the gears; and arms on said rotatable gears adapted to engage said display supports and push them through said guideways.

6. In a merchandise display device, a box having a platform having two concentric superposed sinuously circular guideways arcuately offset so that their paths intersect each other; two series of table-like merchandise display supports located in said guideways; and a plurality of rotatable drivers spaced on a circular line defined by the intersecting points of the sinuous guideways, said drivers each being adapted to engage the display supports at the point where the sinuous paths intersect and move the display supports of one series in a clockwise direction and those of the other series in a counterclockwise direction through their respective guideways from the points of intersection to adjacent points of intersection, the driving means and the number and relative positions of the display supports in each series being such that at the points of intersection the display supports moving in opposite directions just passing each other although appearing as though they would collide.

WILLIAM W. NARAMORE
